UNITED STATES PATENT OFFICE.

EUGENE GASSMANN, OF BROOKLYN, NEW YORK, ASSIGNEE TO EISEMANN MAGNETO CO., OF BROOKLYN, NEW YORK, A CORPORATION OF NEW YORK.

ELECTRICAL IGNITING DEVICE FOR INTERNAL-COMBUSTION ENGINES.

1,108,739.

Specification of Letters Patent.

Patented Aug. 25, 1914.

Application filed August 6, 1913. Serial No. 783,341.

To all whom it may concern:

Be it known that I, EUGENE GASSMANN, a citizen of Germany, and a resident of the borough of Brooklyn, county of Kings, 5 and State of New York, have invented a certain new and useful Improvement in Electrical Igniting Devices for Internal-Combustion Engines, of which the following is a complete specification.

10 It is well known in the art, that in electrical igniting devices for internal combustion engines, the point of ignition must be advanced or retarded according to the variations in the speed of the engine, and 15 that such ignition devices are usually equipped with mechanism for effecting this automatically, as the speed of the engine is increased or reduced. This mechanism to be effective, must be constructed so as to be 20 highly sensitive, and prompt to respond to every change in speed.

The mechanism is actuated by variations in the speed of a rotating part of the ignition device, which, as a rule, is driven by 25 a transmission from the engine, and as the speed of the internal combustion engines, used on automobiles, motor boats, etc., is very much more affected by changes in the load than the speed of other engines, which 30 can be constructed heavier in proportion to the power to be produced, it is, consequently, much more abruptly and frequently reduced and increased, and the operation of the mechanism for advancing or retarding the 35 ignition point, correspondingly of an automobile, motor boat, etc., engine, will be so much more frequent and rapid. The most frequent changes in the speed of these engines, take place at the starting of the engine, and before the vehicle, or boat, gets 40 fairly under way, and during such periods, the ignition point regulating devices are kept in a constant state of more or less violent vibration, much more so than when 45 the engine is run at higher speeds than its calculated normal. Furthermore, while the engine runs at such low speeds the rotating of the magneto shaft is influenced by the 50 alternating resistance and attraction of the pole pieces by the field magnets, these alternating factors tending in one instance to retard, and in the other, to accelerate its rotation. This interference is practically nullified when the engine is run at its normal 55 speed or above, while the ignition point

regulating device is caused to act most frequently during the period from the starting of the engine, and before its normal, or higher, speed is attained, though the economically efficient running of the engine 60 may not, and in most engines does not, require the changing of the ignition point during the period.

The efforts, heretofore made, to obviate the detrimental effect thereof by providing 65 variously constructed cushioning devices, were successful only in reducing the noise, and only for a brief period of time, but are wholly ineffective to remedy the cause and main defect, the vibrating and the consequent wearing out of the parts of the 70 regulating device, and the impairing, in fact, destroying, of its efficiency. The stated considerations show that the hammering and wearing out of the parts of the 75 mechanism, can only be obviated by the prevention of the almost constant changing of the ignition point, back and forth, during this period at low speeds, but so that the capacity of the device for regulating, 80 that is, advancing and retarding of the ignition point, when the engine is run at the higher speeds, is not impaired.

Taking into consideration the fact, that 85 internal combustion engines of average construction do not require the ignition point to be advanced during the increase in their speed from zero to nearly the calculated normal, and will work and run satisfactorily when making a higher or lower number 90 of revolutions per minute within the stated range, I have devised means for automatically arresting the operating parts of the ignition point regulating device, during the periods, in which the engine runs at speeds 95 below a predetermined limit, and again automatically releasing them when the speed of the engine rises above it, the arresting, holding, and again releasing of these operating parts being always effected 100 automatically by the variations in the speed of the engine. By these means the object of my invention, to relieve the operation of the ignition point regulating devices of the stated defects, is accomplished.

The practical embodiment of my invention in the construction of an operative device are based upon the stated considerations and the construction of the herein shown and described automatic locking at- 110

2 attachment for such regulators of the ignition point is designed upon these principles.

In the accompanying drawings, the application of my invention to the ignition point regulating device of a magneto ignition system is shown. It is, however, equally well applicable to other, similarly constructed regulating devices, which are actuated by variations in the speed of the rotating part, whereon they are mounted.

5 In these drawings Figure 1 is a longitudinal sectional view, partly elevation, of those parts of a magneto, required to be shown for the purposes of these specifications; Figs. 2 and 3 illustrate only the parts of the automatic locking device, drawn on a somewhat larger scale; Fig. 2 being a sectional view on line 2--2 indicated in Fig. 3; and Fig. 3 an end view thereof.

10 Referring now to Fig. 1, the parts designated *a* and *a'* are the field magnets and *b* the pole pieces; *b'* the armature winding; *c* is the rotating shaft and *d* the shaft, whereon the driven pulley (not shown) is set. This shaft *d* is rotatably mounted within the squared and internally recessed end of the armature shaft *c*, upon whose other end the make-and-break mechanism is fixed, adjacent thereto, in the casing. Shaft *d* is provided with spiral ridges *c'* and the block *e*, fitted to smoothly slide in the recess *c''* with corresponding grooves *c'''*. By shifting block *e* upon the shaft *d*, the shaft *c* is partly turned, ahead of, or behind the driven shaft *d* whereon the driving pulley is fixed. This is effected by the fly-heads *f*, pivoted in lugs *h*, secured to, or made integral with the shaft *c*. They are connected by links *g* to trunnions *e''* of the block *e* (see Fig. 3), 20 engaging in, and projecting from, the slots (not shown), in the side-walls of recess *c''* in the shaft *c*. Thus the block *e* is reciprocated by the variations in the rotating speed of the shaft. A compressible spiral spring *s* is usually set, as shown in Fig. 1, on the inner end of shaft *d*, between the block *e* and the rear end of the recess *c''*, and set to yieldingly hold, and to assist in returning the block *e* to the forward end of shaft *c*, 25 when its rotating speed is reduced. These parts constitute such a regulating device, as were heretofore used for the advancing or retarding of the point of ignition, according to the speed of the engine, this being effected by the fly-heads shifting the block sleeve on the shaft *d*, whereby the armature shaft *c* is turned from right to left, or vice versa, and the position of the make-and-break mechanism, relative to the driven shaft *d* changed, and the closing and breaking of the primary circuit accelerated, or 30 retarded.

To preserve the necessary sensitiveness of the governing device, and yet to avoid the destructive effect of its rapid reciprocating

vibrations, occurring during the running of the engine at lower than what may be designated as its "normal" speed, I combine with it an automatically operating locking device, constructed as follows: Recesses *j* (see Fig. 2) are made in the block *e*, and catches *n* are supported on the free ends of flat springs *k*, having their other ends secured to the shaft *c*. The catches *n* are set on the ends of stems *m*, secured in fly-blocks *l*, in position to engage in the recesses *j* when the block sleeve *e* is at the outer end of the recess *c''* of the armature shaft *c*. Springs *k* are set to press the catches *n* into the recesses *j*, and the fly-blocks *l*, secured to the same free ends of the springs *k*, have the same purpose as the fly-heads of a centrifugal governor—they act, when propelled by centrifugal force, to withdraw the catches *n* from the recesses *j*. Springs *k* are dimensioned, tempered and set, to hold the fly-heads *f* in the position, close to shaft *c* as shown in Fig. 1, and the catches *n*, in engagement with the edges of the forward ends of the recesses *j*, as long as the rotary speed of the shaft *c* does not exceed a pre-determined limit. This limit should be less than what would correspond to normal speed of the engine. Recesses *j* are provided in the side-walls of shaft *c* (see Fig. 3), into which catches *n* may be received when withdrawn from the recesses *j*, circular perforations *o* are provided, in connection with the recesses *j*, for their stems *m*, connecting them with the fly-blocks *l*. The mass and weight of fly-blocks *l* should be proportioned to the rate of speed at which they are to act, and, of course, also to the elastic resistance of the springs. Before the engine is started, or whenever its speed drops below that, at which the fly-blocks *l* are to act, the parts of the locking device will be in the position, shown in Fig. 1, the block sleeve *e* is held immovable, and the ignition point constant. This condition is maintained until the speed of the engine rises to, or above, that, at which an advance of the ignition point is required. The fly-heads *f* being correspondingly proportioned, the centrifugal force, acting thereon, will then be sufficient to overcome the elastic resistance of springs *k*; the fly-heads will move away from shaft *c*, thereby withdrawing catches *n* from the recesses *j*, and the block *e*, being thus released, and free to yield to the similar action of the fly-heads *f*, will be moved toward the rear end of recess *c''*. Thereby the shaft *c*, whereon the make-and-break mechanism is mounted, is turned in the direction of its rotation and in advance of shaft *d*, and, the position of the cams, acting upon the movable contact pieces, being fixed, the point of ignition is thereby correspondingly advanced. When the speed of the engine decreases, the block *e*

e is moved toward the forward end of the shaft *d*. The lower faces *n'* of the catches are beveled off, toward the inner end of recess *c*², to enable block *e* to slide thereunder when returning from its extreme rearward position. The catches *n* drop into the recesses *j* when the block *e* reaches its starting position, at the extreme forward end of the recess *c*², and lock it, as hereinbefore explained.

Extended tests of the device, herein shown and described, in practical use, have demonstrated that a locking device, constructed upon the stated principles, attains the objects of my invention in every respect, and does not, in any way, impair the effectiveness of the device for automatically advancing or retarding the ignition point, wherewith it is combined.

20 I claim as my invention:

1. The combination with a regulating device, comprising a shaft, rotatably mounted in bearings, means for rotating the shaft; a movable part, and mechanism, actuated by variations in the speed of the rotating shaft, mounted thereon, of means for locking the movable part, thereby suspending the action of the regulating device, and of means, operatively connected with the locking means, and actuated by an increase in the speed of the rotating shaft, to, or above, a predetermined limit, and to release the movable part of the regulating device when the said shaft is rotated at, or above, the predetermined speed.

2. The combination with a regulating device, comprising a rotating shaft, a movable part and mechanism for moving it, mounted on, and actuated by variations in the speed of the rotating shaft, of spring actuated means for locking the movable part of the regulating device, and reversely operable by a predetermined increase in the speed of the rotating shaft, to release the movable part of the regulating device when the said shaft is rotated at, or above, the predetermined speed, substantially as herein shown and described.

3. The combination with a regulating device, comprising a hollow shaft, and means for rotating it; a shaft turnably mounted in the hollow shaft; spiral ridges on the shaft;

a correspondingly grooved sleeve, non-turnably mounted on the shaft, and means, actuated by variations in the speed of the 55 rotating shaft, for reciprocating the sleeve, of a locking device, comprising spring-actuated means adapted to engage the sleeve and to hold it in fixed position on the shaft; and reversely operable by a predetermined 60 increase in the speed of the rotating shaft, so as to release the sleeve and hold the locking means from engaging the sleeve when the hollow shaft is rotated at, or above, a predetermined speed; substantially as here- 65 in shown and described.

4. The combination with a regulating device, comprising a hollow shaft, a shaft, provided with spiral ridges, turnably mounted in the hollow shaft; a correspondingly grooved sleeve, non-turnably mounted on the shaft; means for rotating the hollow shaft, and means connected therewith, for reciprocating the sleeve correspondingly to the speed, at which the hollow shaft, is 70 rotated, of a locking device, comprising recesses in the sleeve, bolts mounted on springs upon the hollow shaft, and in position to engage in the recesses of the sleeve, and means, connected with the bolts, and 75 operable by centrifugal force at a predetermined increase in the speed of the rotating shaft, for withdrawing the bolts and for holding them withdrawn while the hollow shaft is being rotated at, or above, the 80 predetermined speed; substantially as herein shown and described.

5. The combination with a regulating device, comprising, *inter alia*, a hollow shaft, a shaft, provided with spiral ridges, turnably mounted in the hollow shaft; a correspondingly grooved sleeve, non-turnably mounted on the shaft and means for reciprocating the sleeve, of a locking device, comprising recesses in the sleeve, springs secured to the hollow shaft, and weighted bolts, adapted to engage the recesses in the sleeve, secured to the springs; substantially as herein shown and described.
